UNITED STATES PATENT OFFICE.

ROBERT SCHORR, OF SAN FRANCISCO, CALIFORNIA.

ROTARY PUMP OR COMPRESSOR.

1,257,744.

Specification of Letters Patent. Patented Feb. 26, 1918.

Application filed March 8, 1917. Serial No. 153,290.

To all whom it may concern:

Be it known that I, ROBERT SCHORR, a citizen of the United States, residing at San Francisco, in the county of San Francisco and State of California, have invented new and useful Improvements in Rotary Pumps or Compressors, of which the following is a specification.

The present invention relates to improvements in rotary pumps and compressors. Most of the varieties of pumps of the above character have too small an extent of watertight or sealing surfaces between the inlet and the outlet, thus leading to excessive leakage and consequent low efficiency. The main object of the present invention is to provide an efficient pump by reducing back-slipping and leaking to a minimum, and to accomplish this by providing rotary and stationary elements which coöperate in such a manner as to insure at all times watertight contacts between the suction and the pressure parts of the pumps; and a further object is to provide rotors having ends of such shape as to render it impossible for the fluid to be carried past said ends to the suction inlet.

A further object is to provide a construction of rotary pump such that all joints which serve the purpose of interpolating tight surfaces between the suction and the pressure ends can be accurately finished by machine tools.

In the accompanying drawing, Figure 1 is a cross-sectional view of my improved pump, taken on the line 1—1 of Fig. 2; Fig. 2 is a longitudinal section thereof taken on the line 2—2 of Fig. 1; Fig. 3 is a diagrammatic view, showing how the coöperating rotary elements make with each other a water-tight fit at all stages in their rotation in contact with each other. Fig. 4 is a diagrammatic sectional view illustrating one of the positions of the rotors of the pump; Fig. 5 is a sectional view showing a modification of the pump housing for high speed operation.

Referring to drawing, 1 indicates a pump housing, having a cover 2. Extending through said cover into said housing are shafts 3 and 4, geared together by spur wheels 5 and 6. Fastened to one of the shafts is a driving pulley 7. The shafts 3 and 4 are supported on the outside of the pump housing by a double bearing 8, and in the housing by the bearings 9, 10. The

openings by which the shafts pass through the cover 2 are sealed by stuffing boxes 11. For larger sized pumps stuffing boxes would also be provided at the other end to extend 60 the shafts for the purpose of mounting an additional set of gears and outside bearings, thus eliminating the inside bearings 9, 10. The pump housing and the outside bearings are mounted upon a bed-plate 12. 65

The fluid enters at 13 into a suction chamber 14, and is drawn through an opening 16 into one of two rotor chambers 17 by the suction created by the rapid rotation, in the directions indicated by the arrows, of rotor 18, having portions 19 secured to the shafts 3, 4, and extensions or pistons 21. The space in the rotor chamber 17, unoccupied by the piston 21 becomes in this way alternately filled with fluid, which is forced 70 through opening 22 into the stationary pressure or outlet chamber 23, and thence through the outlet 24, because one of the gaps AB and AC is always closed by one of the pistons while the other piston is forcing 75 the fluid upward through the discharge channel.

The mode of operation is further illustrated in Fig. 4 which shows one of the positions of the two pistons 21. It will be 85 noted that there are at all times parts of the rotor 18 in contact with one or the other of the surfaces BD and CE which are located between the inlet and outlet of the pump. The peculiar shape of the ends or 90 working faces of the pistons is essential for effecting a complete discharge. The piston surface ab, (see Fig. 3,) is so designed as to remain in contact with the edge c of the other piston surface during the travel from 95 A to B, and conversely.

The water space f in each of the water chambers is reduced gradually until it finally disappears altogether.

Each rotor extends through one-half of a 100 cylinder, and each occupies almost one-half of the pump chamber, which it passes through in one revolution. The pump is reversible, but the volumetrical efficiency is somewhat smaller if the rotors turn outward toward 105 the floor line, that is in the opposite direction from the one indicated by the arrows.

In Fig. 5 is shown a modification of the pump housing in which there are provided auxiliary suction inlets 25, and discharge 110 outlets 26. These are necessary if the width of the rotors is restricted. In that case it

would be structurally impossible to provide sufficient areas for the passages 16 and 22 without increasing very considerably the diameter of the pump chamber. Such a narrow arrangement obviously requires greater speed for a given unit capacity, and this modified design is, therefore, advisable for high speed pumps.

Other modifications are possible, as is also 10 the grouping of the two or more single pumps into one housing for the purpose of lifting the fluid in stages.

I claim:—

1. In combination with a housing, two 15 hollow semi-cylindrical rotors revoluble in opposite directions in said housing, said housing having stationary outlet chambers arranged concentrically with the respective rotors.

2. In combination with a housing, two 20 hollow semi-cylindrical rotors having sickle-shaped end surfaces and revoluble in opposite directions in said housing, said housing having stationary outlet chambers arranged 25 concentrically with the respective rotors.

3. In combination with a housing, two 30 hollow semi-cylindrical rotors and revoluble in opposite directions in said housing having end surfaces arranged to insure riding 35 contact of an end of one rotor upon an adjacent end of another rotor during the end of the discharging period, said housing having stationary outlet chambers arranged concentrically with the respective rotors.

4. In combination with a housing, two 35 hollow semi-cylindrical rotors revoluble in opposite directions in said housing, the paths of said rotors overlapping each other 40 and being in contact with corresponding concave surfaces of the stationary outlet chambers, said housing having stationary

outlet chambers arranged concentrically with the respective rotors.

5. In combination with a housing, two 45 hollow semi-cylindrical rotors revoluble in opposite directions in said housing, the paths of said rotors overlapping each other and being in contact with corresponding concave surfaces of the stationary outlet chambers, said outlet chambers communicating with a pump chamber, said housing having stationary outlet chambers arranged 50 concentrically with the respective rotors.

6. In combination with a housing having 55 inlet passages for fluid and stationary outlet chambers, two hollow semi-cylindrical rotors revoluble in opposite directions, and having end surfaces shaped to permit riding contact of a surface of one rotor upon a surface 60 of the other rotor during the end of the discharging period.

7. In combination with a housing having 65 inlet passages for fluid and stationary outlet chambers, two hollow semi-cylindrical rotors revoluble in opposite directions, and having end surfaces shaped to permit riding contact of a surface of one rotor upon a surface 70 of the other rotor during the end of the discharging period, said housing having additional inlet and outlet openings in its side.

8. In combination with a housing having 75 inlet passages for fluid and stationary outlet chambers, two hollow semi-cylindrical rotors revoluble in opposite directions, and having end surfaces shaped to permit riding contact of the surface of one rotor upon the surface of the other rotor during the end of the discharging period, and means for moving the rotors in unison from the outside of the housing.

ROBERT SCHORR.
